PACKAGING SHOELACES AND THE LIKE

Herman A. Moe, Warwick, R. I.

Application July 22, 1941, Serial No. 403,555

9 Claims. (Cl. 28—21)

The present invention relates to the packaging of shoe-laces, corset-laces or similar articles and materials, and more particularly to a method of and means for packaging such articles and materials and the resulting package therefor.

One of the objects of the invention is to provide a method of packaging an article such as a shoe-lace by winding it on itself in overlying spiral coils or turns and applying a U-shaped fastener across the periphery and adjacent the sides of the wound lace to bind the coils together in a compact package.

Another object is to provide a method of the character indicated which comprises winding the shoe-lace or the like in overlying spiral coils with one of its tips serving as an axial core to provide a compact and tightly wound package.

Another object is to provide a method of and apparatus for simultaneously winding a pair of shoe-laces or the like in adjacent side-by-side relationship and applying and clinching a U-shaped fastener around the pair of wound laces to bind them together in a compact self-sustained package.

Another object is to provide an apparatus of the type indicated having a two-part mandrel for winding the shoe-laces and guiding and clinching the legs of the fasteners, with the separate parts of the mandrel relatively movable in an axial direction to adapt the wound laces to be removed therefrom.

Another object of the invention is to provide a method of and apparatus for packaging shoe-laces and the like which produces an improved form of package.

Further objects of the invention are set forth in the following specification which describes the method and a preferred form of apparatus for carrying out the steps of the method, by way of example, as illustrated by the accompanying drawings. In the drawings:

Fig. 1 is a side elevational view of an apparatus incorporating certain novel features of the present invention;

Fig. 2 is an enlarged front elevational view showing the mandrel partly in section and illustrating a pair of shoe-laces wound thereon and a fastener applied thereto to produce a self-sustained package;

Fig. 3 is a part-sectional view similar to Fig. 2 showing one of the mandrel parts moved axially with respect to the other part to adapt the shoe-lace package to be removed therefrom;

Fig. 4 is a view similar to Fig. 2 showing the

relationship of the parts of the mandrel as adjusted for a winding operation;

Fig. 5 is a transverse sectional view on line 5—5 of Fig. 2 showing the overlying spiral coils of the shoe-lace wound on the mandrel;

Fig. 6 is a perspective view of one of the heads of the two-part mandrel showing its axially-projecting key and the radial groove for guiding one of the legs of the fastener;

Fig. 7 is a perspective view of the opposite head of the mandrel showing the spaced axially-projecting blades providing a slot therebetween and the axially-directed slot in one of the axial blades;

Fig. 8 is a perspective view of one form of shoe-lace package produced in accordance with the invention;

Fig. 9 is a part-sectional front view of a modified form of winding mandrel; and

Fig. 10 is a perspective view of one of the heads of the two-part mandrel illustrated in Fig. 9.

Heretofore shoe-laces have usually been put up in loose loops or elongate coils with a pair of the looped laces encircled by a paper band extending throughout a considerable portion of their length to bind them together and prevent them from uncoiling. Such encircling bands usually have advertising matter printed thereon indicating the name or trade-mark of the particular wholesaler, jobber, or retailer by whom they are marketed. The manufacturer must therefore apply different bands to shoe-laces supplied to different customers. As a result, the manufacturer cannot package the shoe-laces as they are made, that is, if they are manufactured before being ordered the laces must be placed in stock and only packaged after the orders are received. If an order for a large quantity of shoe-laces is to be filled from stock considerable time is consumed in packaging the laces before they can be delivered.

In accordance with the present invention shoe-laces may be packaged as they are manufactured and later inserted into individual Cellophane envelopes or other suitable containers having the advertising indicia printed thereon. As a result of applicant's invention orders may be filled by the manufacturer from stock with greater promptness than has heretofore been possible.

The present method of packaging shoe-laces consists in winding them in overlying coils or turns and applying a U-shaped metallic fastener to embrace the wound lace with the crossbar of the fastener extending across the periphery and the legs of the fastener lying adjacent the sides of the package. The ends of the legs of the

fastener may be clinched as the fastener is driven whereby the fastener binds together the coils of the wound lace to prevent displacement or unwinding thereof. Thus the winding of the shoe-lace and the application of the fastener thereto as described produces an attractive compact commercial package.

Preferably, a pair of shoe-laces are wound simultaneously in adjacent side-by-side relationship with the tips at one end of the laces constituting an axial core or support. The ends of the legs of the fastener are preferably bent toward each other or clinched at the center of the package to complete the binding action. It will be understood, however, that the present method of packaging shoe-laces or like articles is applicable for producing practically any form of package. For example, if the usual form of shoe-lace package made up of loosely coiled elongate loops is desired a single fastener may be applied to encircle the pair of looped laces, or a plurality of such fasteners may be applied along its length.

Fig. 1 of the drawings illustrates a machine or apparatus for carrying out the steps of the present method of packaging shoe-laces and like articles of commerce. The apparatus comprises a frame having a base 2 adapted to rest on the base with a horizontal arm 4 projecting laterally therefrom adjacent its upper end. Rockably mounted on a pivot-pin 5 at the upper end of the column 3 is a fastener-applying mechanism 6 which overlies the horizontal arm 4 and is adapted to cooperate with a shoe-lace coiling or winding mechanism 7 supported on the other end of the arm. The fastener-applying mechanism 6 illustrated in Fig. 1 of the drawings is of well-known construction as shown and described in United States Letters Patent to Arthur H. Maynard, No. 2,045,397, issued June 23, 1936. Suffice it to state herein that the fastener-applying mechanism comprises a magazine-arm 8 for containing a supply of U-shaped metallic fasteners or staples S and slidably mounted in a head at the outer end of the arm is a driver 9 adapted to be reciprocated to drive the staples S from the magazine.

The driver 9 of the fastener-applying mechanism 6 is adapted to be actuated by an arcuate double-sided lever 10 pivotally mounted intermediate its ends on the extended ends of the pin 5 and having one end connected to the driver 9 by means of links 11. The opposite end of the lever 10 is pivotally connected to the outer end of a link 16 which together with a second link 17 constitute a toggle. The lower ends of the toggle links 16 and 17 are connected to each other and to a head 18 adjustably mounted on a plunger-rod 19, while the upper end of the toggle link 17 is pivotally connected to the column 3. The plunger-rod 19 extends vertically adjacent the column 3 and its lower end is connected to one end of a foot-treadle 20 pivotally mounted intermediate its ends on the base 2. By means of this construction depression of the foot-treadle 20, acting through the plunger-rod 19, head 18 and toggle links 16 and 17 will rock the lever 10 in counterclockwise direction, as viewed in Fig. 1, to depress its forward end. This motion of the lever 10 will first cause the magazine-arm 8 to be swung downwardly toward the winding unit 7 and thereafter cause the driver 9 to be reciprocated to apply a fastener S. A spring 15 connected at its upper end to the head 18

of the plunger-rod 19 and anchored at its lower end to the column 3 is adapted to restore the fastener-applying mechanism to its inoperative position illustrated in Fig. 1 when the treadle 20 is released.

Referring to Figs. 1 and 2 of the drawings, the shoe-lace coiling or winding mechanism 7 comprises a mandrel having two parts 21 and 22 rotatably mounted in bearings 23 and 24 formed as part of standards supported on and fastened to a suitable rest on the arm 4. The mandrel part 21 comprises a shaft 25 rotatable in the bearing 23 and a head 26 at its end. The head 26, shown in detail in Fig. 7, is in the form of a generally circular flange having one face abutting the bearing 23 and a pair of blades 28 and 29 extending laterally from its opposite face to provide an axial opening or slot 30 therebetween. One of the blades 28 is provided with a slot 31 extending at right-angles to the slot 30. A radially-extending groove 32 in the forward face of the head 26 is disposed in alignment with the slot 31 to serve as a guide for one leg of a fastener S as it is driven by the fastener-applying means 6. The lower end of the groove 32 is gradually curved or rounded into the end of the slot 31, as indicated at 33 in Fig. 4, to cause it to clinch the end of the leg of a fastener S as it is driven.

Mounted on the end of the shaft 25 extending outwardly from the bearing 23 is a crank-arm 37 fixedly connected to the shaft by means of a key 38 and nut 39. A handle 40 rotatably connected to the outer end of the crank-arm 37 is slidably longitudinally in its bearing and has a detent-pin 41 at its inner end engageable with a recess 42 in the standard of the bearing 23. A spring 43 positioned between a flange on the handle 40 and the side of the crank-arm 37 normally tends to slide the handle in an axial direction to engage the detent-pin 41 with the recess 42.

The mandrel part 22 comprises a shaft 46 rotatably mounted in the bearing 24 and having a head 47 at its forward end and a handle or knob 48 at its opposite end. The head 47, shown in detail in Fig. 6, comprises a generally circular flange similar to the radial flange of the mandrel part 21 and a laterally-projecting key 50 of a shape and contour to adapt it to fit into the open end of the slot 30 between the blades 28 and 29 of the mandrel part 21. The mandrel part 22 is also provided with a radial groove 51 for guiding a leg of the staple S and the groove is curved inwardly at its lower end as indicated by the reference character 52 to adapt it for clinching the end of the staple leg. The shaft 46 of the mandrel part 22 is slidably longitudinally of its axis in the bearing 24 to withdraw the head 47 laterally from the head 26 of the mandrel part 21 and a coiled spring 53 mounted on the shaft and acting between the head and bearing 24 normally tends to move the head 47 toward the head 26 to project the key 50 into the slot 30 in the manner indicated in Fig. 4.

The arrangement of the fastener-applying mechanism 6 with respect to the winding mandrel 21, 22 is such that when the detent-pin 41 of the handle 40 on the crank-arm 37 is engaged in the recess 42 in the standard for the bearing 23 the driver 9 of the fastener-applying mechanism is in alignment with the grooves 32 and 51 in the mandrel heads 26 and 47, see Figs. 2 and 5. One form of apparatus having now been described in detail, the mode of operation of the

device to perform the steps of the method is as follows.

To start a winding operation the tips T at one end of a pair of shoe-laces L are inserted into the slot 30, see Fig. 2. The handle 40 is slid axially to release the detent-pin 41 from the recess 42 in the standard of the bearing 23 and the crank-arm 37 is then rotated by means of the handle. Rotation of the crank-arm 37 keyed to the shaft 25 will rotate the mandrel part 21 and due to the engagement of the key 50 on the head 47 with the slot 30 in the head 26 both mandrel parts 21 and 22 will turn as a unit. As the mandrel 21, 22 is rotated it will wind the pair of shoe-laces L around the blades 28 and 29 in a series of overlying spiral coils or turns in side-by-side relationship in the manner illustrated in Figs. 2 and 5 with the heads 26 and 47 guiding the coils of the shoe-laces as they are being wound. As the length of the slot 30 is substantially equal to the length of the tips T of the laces L the tips will eventually serve as a core or axial support for the coiled laces. Rotation of the mandrel 21, 22 by means of the handle 40 is continued until the entire length of the shoe-laces is wound on the mandrel as illustrated in Fig. 5.

After the pair of shoe-laces L have been fully wound the operator releases the handle 40 which is actuated by the spring 43 to engage the detent-pin 41 with the recess 42 in the standard of the bearing 23 to align the grooves 32 and 51 of the mandrel parts 21 and 22 with the driver 9 of the fastener-applying mechanism 6. The operator then depresses the treadle 20 which acting through the plunger-rod 19 and toggle links 16 and 17 will rock the lever 10 on its pivot 5 in contraclockwise direction. As the lever 10 is rocked in this manner it will first act to rock the magazine-arm 8 downwardly to engage its forward end with the top of the mandrel 21, 22 and thereafter it will operate the driver 9 to apply a fastener S. As the driver 9 and fastener S are in alignment with the grooves 32 and 51 in the heads 26 and 47 of the mandrel parts 21 and 22 the legs of the U-shaped staple S will be guided by the grooves as the staple is driven. At the end of the driving stroke the ends of the fastener legs will engage the curved portions 33 and 52 at the bottom of the grooves 32 and 51 and be deflected inwardly toward each other to clinch them under the first coils of the wound laces adjacent the tips T, see Fig. 2. In this way the fastener S will be applied in position around the periphery and sides of the wound laces and clinched at the center thereof to bind the shoe-laces together in a compact self-sustained package P.

To remove the shoe-lace package P from the mandrel 21, 22 the operator withdraws the mandrel part 22 axially from the mandrel part 21. For this purpose the operator may grasp the knob 48 at the end of the shaft 46 and slide the mandrel part 22 axially against the action of the spring 53 to the position illustrated in Fig. 3. The package P may then be removed from the mandrel head 26 by disengaging it from the blades 28 and 29, the transverse slot 31 permitting the clinched ends of the fastener S to slide outwardly therethrough.

The resulting package P may comprise a pair of shoe-laces or like articles L wound in overlying spiral coils in adjacent side-by-side relationship with the tips T providing an axial sup-

port and the fastener S securely binding the coils together.

After the package P is removed from the device the operator releases the knob 48 of the mandrel part 22 which will then be automatically projected toward the opposite mandrel part 21 by the spring 53. At the end of the return movement of the mandrel part 22 the key 50 thereon will enter the open end of the slot 30 between the blades 28 and 29 to key the two parts of the mandrel together for rotation as a unit. The operator also releases the foot-treadle 20 and the fastener-applying mechanism 6 will thereupon be returned to the inoperative position illustrated in Fig. 1 by the spring 15 which acts on the plunger-rod 19 and toggle links 16 and 17 to rock the lever 10 in clockwise direction whereby to raise the driver 9 and lift the magazine-arm 8. As the driver 9 is raised in the head of the fastener-applying mechanism 6 the supply of fasteners S in the magazine-arm 8 are advanced by suitable means to position the foremost fastener beneath the driver to be driven during the next operation of the treadle 20.

It will be understood that the present drawings are for purposes of illustration only and that the mandrel may be rotated, the fastener-applying means operated and the mandrel parts moved axially of each other by other means than those herein shown and described.

Figs. 9 and 10 illustrate a modified form of construction of the winding mandrel. In this form of construction the two parts 60 and 61 of the mandrel are of identical construction but of opposite hand. The mandrel parts 60 and 61 each has a head 62 and laterally-extending spaced blades 63 and 64 providing a slot 65 therebetween. A radial groove 66 and a transverse slot 67 is provided in the blade 63 of each head with the lower end of the groove curved as indicated at 68. A spring 69 acting between the bearing 24 and the head of the mandrel part 61 yieldingly urges the latter toward the head of the other mandrel part 60. Thus the mandrel parts 60 and 61 cooperate to form a continuous axial slot 65 and the transverse slots 67 aline to provide a continuous slot across the upper blades 63. With the construction illustrated in Figs. 9 and 10 the mandrel parts 60 and 61 may be suitably connected or their shafts geared together to adapt them for rotation as a unit.

The winding mandrel 60, 61 may be operated in the same manner as explained with respect to the mandrel 21, 22 illustrated in Figs. 1 to 7 to wind a pair of shoe-laces L and a fastener S may be applied by the fastener-applying mechanism 6 by the same instrumentalities as illustrated in Figs. 1 and 2. With this form of construction, however, the blades 63 and 64 of each mandrel part 60 and 61 extend to the center of the package P only to facilitate its removal.

It will be observed from the foregoing specification that the present invention provides an improved method of and apparatus for packaging shoe-laces and a novel form of shoe-lace package produced thereby. It will be observed also that the present invention provides for packaging the shoe-laces as they are manufactured so that orders therefor may be quickly filled from stock. It will be observed further that the method of the present invention facilitates the operation of packaging shoe-laces with a comparatively simple and inexpensive apparatus.

While a preferred method and suitable apparatus for carrying out the steps of the method

are herein described and illustrated it will be understood that modifications may be made in the steps of the method and in the form of construction of the apparatus without departing from the spirit or scope of the invention. For example, the mandrel may be so formed as to wind a package of any desired contour, such as with the usual elongate coils, and the fasteners may embrace the entire shoe-lace package instead of being clinched at the center of the package as in the illustrated embodiment. Therefore, without limiting myself in this respect, I claim:

1. The method of packaging shoe-laces or the like which comprises winding a shoe-lace in overlying turns, applying a U-shaped fastener to embrace all of the turns from the periphery of the winding to its axis, and clinching the ends of the legs of the fastener to bind the turns together and provide a self-sustained package.

2. The method of packaging shoe-laces or the like which comprises simultaneously winding a pair of shoe-laces in overlying turns in adjacent side-by-side relationship, applying a U-shaped fastener to embrace all of the wound turns of the pair of shoe-laces, and clinching the ends of the legs of the fastener to bind together the pair of wound laces and the turns of each lace and provide a self-sustained package.

3. The method of packaging shoe-laces having tips at their ends which comprises gripping the tips at one end of a pair of laces and rotating the same to cause the laces to wind thereon in adjacent spiral coils, applying a U-shaped fastener across the periphery of the coiled laces and adjacent the opposite sides thereof, and clinching the ends of the legs of the fastener inwardly toward each other at the center of the wound coils to bind the pair of laces together and retain them in coiled form.

4. A package of shoe-laces or the like comprising a lace wound in overlying spiral coils with a U-shaped fastener embracing the periphery and sides of the wound coils with the ends of its legs clinched at the axis of the coils to provide a self-sustained package.

5. A package of shoe-laces or the like comprising a pair of laces wound in overlying spiral coils arranged in adjacent side-by-side relationship with a U-shaped fastener extending across the periphery and adjacent the sides of the wound coils with the ends of its legs clinched at the axis of the coils to provide a self-sustained package.

6. A device for packaging shoe-laces and the like comprising a rotary mandrel having means for holding one end of the lace to wind it on

itself in spiral coils and means for supporting the coils at the sides, fastener-applying means supported adjacent the mandrel in cooperative relation thereto to apply a fastener with its cross-bar overlying the periphery of the wound coils and its legs straddling the sides thereof, and means on the mandrel for bending the legs of the fastener to clinch them through the axial center of the coils.

7. A device for packaging shoe-laces and the like comprising a rotary winding mandrel having means adjacent its axial center for holding the end of a lace and portions adapted to abut the edges of a lace wound in spiral coils therebetween, fastener-applying means supported in cooperative relation to the mandrel and adapted to drive a fastener with its legs straddling the sides of the wound coils of the lace on the mandrel, and clinching means on the mandrel for bending the ends of the legs of the fastener toward each other to bind the coils of the lace together to form a substantially cylindrical self-sustained package.

8. A device for packaging shoe-laces and the like comprising a mandrel having an axial slot to receive a shoe-lace tip and a second slot extending at right-angles to the plane of the first-mentioned slot, means for rotating the mandrel to wind the lace in overlying spiral coils, and fastener-applying means cooperating with the mandrel for applying a U-shaped fastener through the second-mentioned slot in the mandrel to embrace the coils of the wound lace.

9. A device for packaging shoe-laces and the like comprising a mandrel having two parts relatively movable axially with each part having a head, at least one of the parts of the mandrel having spaced blades extending at right-angles to the face of the head to provide an axial slot therebetween for receiving the ends of a pair of laces and at least one of the spaced blades having a slot therein extending at right-angles to the slot between the blades, means for rotating the mandrel to wind the pair of laces thereon between the heads, and fastener-applying means adapted to cooperate with the mandrel for applying a U-shaped fastener adjacent the sides of the pair of wound laces and through the second-mentioned slot in the mandrel to embrace the coils of the wound laces, the heads of the mandrel having radial grooves for guiding the legs of the fastener into the second-mentioned slot in the mandrel with curved portions adjacent their ends for deflecting the ends of the legs of the fasteners to clinch the fastener around the wound laces.

HERMAN A. MOE.
